UNITED STATES PATENT OFFICE.

RAY H. FITZ GERALD, OF PITTSBURGH, PENNSYLVANIA.

DISPENSING AND DISPLAYING CARTON.

1,378,534.

Specification of Letters Patent. Patented May 17, 1921.

Application filed June 23, 1919. Serial No. 306,197.

To all whom it may concern:

Be it known that I, RAY H. FITZ GERALD, a citizen of the United States, and a resident of Pittsburgh, in the county of Allegheny and State of Pennsylvania, have invented certain new and useful Improvements in Dispensing and Displaying Cartons; and I do hereby declare the following to be a full, clear, and exact description of 10 the invention, such as will enable others skilled in the art to which it appertains to make and use the same.

This invention relates to improvements in dispensing and display cartons and more particularly to such as are made of paper or card board,—one object of the invention being to provide a carton from which cylindrical articles can be readily dispensed, and to so construct the device as to provide a tray 20 in front of the discharge opening, which shall be formed integral with the stock from which the body of the carton is made.

With this and other objects in view, the invention consists in certain novel features 25 of construction and combinations of parts as hereinafter set forth and pointed out in the claims.

In the accompanying drawings; Figure 1 is a view showing the blank from which the 30 body of the carton and the tray are made; Fig. 2 is a view of the blank from which the inclined bottom member is made; Fig. 3 is a perspective view of the inclined bottom member, and Fig. 4 is a perspective view of 35 the assembled device.

The body of the carton 1 is made rectangular in form and comprises front and back members 2, 3 and side members 4, 5 integral therewith. The side members are provided 40 at their upper ends with flaps 6 and the back member 3 is made at its upper end with a flap 7 provided with a gluing flange 8,—the flaps 6 and 7 being bent to form the top of the carton. A flap 9 may be provided 45 at the upper end of the front 2 and utilized for advertising purposes. Flaps 10, 10 are provided at the lower ends of the sides 4, 5, and coöperate with bottom member 11 at the lower end of the back 3 to form the bottom 50 of the carton. The bottom member 11 is made with an extension 12 from which a tray 13 is formed to receive articles from the carton, through a discharge opening 14. The portion 15 of the extension 12 forms the 55 bottom of the tray, and said extension is folded on the lines 16, 17, 18 to form the

front wall 19 of the tray,—the end portion 20 being bent so as to be disposed parallel with the bottom 15. The front 4 of the tray thus comprises part of said extension folded 60 upon itself. The extension 12 is made with a hole 21 (Fig. 1) to form a notch 22 in the front wall of the tray as shown in Fig. 3. The ends 23, 23 of the tray are cut from the stock of the carton at the lower end of the 65 front 2 and are integral with the sides 4, 5. The trays ends 23 are made with tabs 24 which enter between the folds of the front wall 19 of the tray.

The end members 23, 23 are provided with 70 tongues 27 which overlie the bottom of the tray and may project under the end portion or flange 20 of the front wall 19. The tongues 27 are provided with other tongues 27^a, 27^a, which may be inserted, with the tabs 75 24 between the folds of the front wall 19 of the tray.

Located within the lower portion of the carton, is an inclined bottom member 25 which is so constructed and placed in the 80 carton as to provide a platform 26 inclining downwardly and forwardly from the rear member 3 of the carton to the front thereof, its front edge terminating at the bottom of the discharge opening 14. The bottom 85 member 25 is provided with an upright member 26^a which depends from the upper edge of the inclined platform 26 and lies against the back member 3 of the carton. From the lower edge of the upright member 90 26^a, a base member 28 extends forwardly and rests upon the bottom of the carton. The base member 28 terminates rearwardly of the front of the carton and is made with an upturned flange 29 which serves as a brace 95 for the intermediate portion of the inclined platform 26. The upturned flange 29 is provided with a plurality of upstanding tongues 30 (which may be located at the end portions of said flange) and these 100 tongues extend through notches 31 made in the side edge portions of the platform and project upwardly above the upper face of the latter at points rearwardly of the front lower edge of said inclined platform. 105

The inclined platform of the bottom member will tend to cause the cylindrical articles within the carton to move forwardly, but the upstanding tongues will act as baffles to hold back the major bulk of the articles, 110 permitting only the front vertical tier of articles to be disposed in a vertical plane in

front of that of said tongue. When an article passes through the discharge opening 14 and enters the tray, the next article in the front tier will drop into position and an 5 article will move from the top of the next tier to the top of the front tier of articles, and this will continue, as articles pass through the discharge opening, until only two articles remain on the bottom inclined 10 platform. These last two articles will be held back by the tongues 30, and the merchant may cause them to pass over said tongues by jarring or shaking the carton. When an article is in the tray, it will hold 15 back the article in line with the discharge opening.

Various changes might be made in the details of construction of my invention without departing from the spirit or limiting its 20 scope and hence I do not wish to restrict myself to the precise details herein set forth.

Having fully described my invention what I claim as new and desire to secure by Letters-Patent, is:—

25 1. The combination with the body of a carton having a discharge opening, of a tray in front of said carton, the parts of said tray being formed from the same blank from which the body of the carton is formed,

and a separate bottom member within the 30 carton and comprising an inclined platform extending from the back of the carton to the bottom of said discharge opening and tongues projecting upwardly from the upper face of said inclined platform rear- 35 wardly of the discharge opening.

2. A blank for a carton comprising front, back, side, and bottom members, portion of the front member cut away forming a discharge opening and end members for a tray, 40 an extension from the bottom member to form the bottom of a tray and a portion of said extension being foldable upon itself to form a front for said tray, the portions forming the ends of the tray having tabs 45 to enter between the folds of the front of the tray, and the portions forming the ends of the tray having tongues to overlie the bottom of the tray and said tongues having other tongues to enter between the folds of 50 the front of the tray.

In testimony whereof, I have signed this specification in the presence of two subscribing witnesses.

RAY H. FITZ GERALD.
